Attorneys

UNITED STATES PATENT OFFICE.

PHILIP A. MYERS, OF ASHLAND, OHIO, ASSIGNOR TO F. E. MYERS AND BROTHER, A COPARTNERSHIP CONSISTING OF FRANCIS E. MYERS AND PHILIP A. MYERS, OF ASHLAND, OHIO.

PUMP-STAND.

1,263,459.

Specification of Letters Patent. Patented Apr. 23, 1918.

Application filed August 9, 1917. Serial No. 185,249.

To all whom it may concern:

Be it known that I, PHILIP A. MYERS, a citizen of the United States, residing at Ashland, in the county of Ashland and State of Ohio, have invented certain new and useful Improvements in Pump-Stands, of which the following is a specification, reference being had therein to the accompanying drawings.

This invention relates to pump stands and has for its object to provide a method of mounting the reservoir or air chamber of a pump so that it may be placed accurately in line with the pump piston and may be turned so as to bring the spout into different positions.

In the accompanying drawings, Figure 1 is a perspective of a pump stand; and Fig. 2 is an enlarged perspective of the parts constituting the invention.

The invention is shown as adapted to tubular well stands, but this is merely by way of illustration. The drawing shows a well stand 1 fast to which is the pump stand 2. A pump head 3 is connected rigidly to the pump stand 2 in any desired way, the connection here shown being made by screws 4. The reservoir or air chamber 5 of the pump is carried on the pump stand 2 and is adapted to be supported by the stand in such a way that the reservoir may be rotated on the stand so as to cause the spout 6 to project in any desired direction.

The pump head 3 carries two curved clamping members 7, which, as shown, are integral with the pump head 3. Evidently they may be made as separate parts and fast to the pump head in any desired way. These curved clamping members 7 are constructed to partly surround and closely fit the upper portion 8 of the reservoir, which for this purpose is made cylindrical in shape. A bolt 9 passes through the two clamping members 7 and as the radius of the curved part of these clamping members is substantially the same as the radius of the cylindrical portion 8 of the reservoir the clamping members serve to center the reservoir accurately so that it will be always in line with the piston rod 10 of the pump. Clearly, the piston rod may be operated by any desire mechanism, that shown comprising the usual handle 11 being merely for illustration.

To position the reservoir 5 on the pump 55 the clamping members 7 are permitted to

expand slightly by withdrawing the bolt 9, whereupon the reservoir may be placed on the pump stand in its proper position. The clamping members 7 are then tightened around the cylindrical portion 8 of the reservoir by tightening the bolt 9 whereby the reservoir is centered accurately relatively to the pump stand and the piston rod, thus preventing any binding of the rod as it moves up and down through the reservoir.

It will be understood that the part 5 has been referred to as a "reservoir" or "air chamber" by way of illustration only. The invention is well adapted to pumps having submerged cylinders, in which cases a reservoir or air chamber is desirable, but it is also equally valuable in connection with other types of pump. It may, for example, be employed on the ordinary lift or suction pump having a pump cylinder.

While I have shown and described one embodiment of the invention it will be understood that the same has been chosen for purposes of illustration only and that I do not desire to be limited to the details of construction shown and described, for obvious modifications will occur to a person skilled in the art.

Having thus fully described my invention, what I claim as new and desire to secure by Letters Patent, is:

1. In a pump, a pump stand, a pump rod and a reservoir supported by said pump stand, and two clamping members fast to said pump head, and partly surrounding the upper end of said reservoir.

2. In a pump, a pump stand, a pump head and a reservoir supported by said pump stand, said reservoir having a cylindrical portion, and two curved clamping members fast to said pump head and partly surrounding said cylindrical portion of said reservoir.

3. In a pump, a pump stand, a pump head and a reservoir supported by said pump stand, said reservoir having a cylindrical portion, two curved clamping members fast to said pump head and partly surrounding said cylindrical portion of said reservoir, and fastening means passing through said pump head and said clamping members, and serving to draw said clamping members tightly against said reservoir.

4. In a pump, a pump stand, a reservoir rotatably carried by said stand, a pump head

fast to said pump stand, and clamping members carried by said pump head and within which said reservoir rotates.

5. In a pump, a pump stand, a reservoir rotatably carried by said stand and having a cylindrical portion, a pump head fast to said pump stand, and curved clamping members carried by said pump head and adjustable to surround tightly the cylindrical portion of said reservoir.

6. In a pump, a pump stand, a reservoir rotatably carried by said stand and having a cylindrical portion, a pump head fast to said pump stand, curved clamping members carried by said pump head and adjustable to surround the cylindrical portion of said reservoir, and fastening means passing

through said clamping members, and serving to draw said members tightly against the cylindrical portion of said reservoir.

7. In a pump, a pump stand, a reservoir rotatably supported by said stand and having a cylindrical portion, a pump head fast to said pump stand, and extending alongside said cylindrical portion of said reservoir, two curved clamping plates fast to said pump head, and closely surrounding the cylindrical portion of said reservoir, and a bolt passing through said clamping plates and serving to draw them tightly against the cylindrical portion of said reservoir.

In testimony whereof, I affix my signature.

PHILIP A. MYERS.
